ANTIDRIP DEVICE FOR BOTTOM
CEMENTING MACHINES

John William Pratt, Leicester, England, assignor
to United Shoe Machinery Corporation, Flem-
ington, N. J., a corporation of New Jersey

Application September 20, 1947, Serial No. 775,303
In Great Britain October 15, 1946

1 Claim. (Cl. 91—39)

1

This invention relates to devices for preventing any surplus coating material, such as cement from dripping from the applying brush of a machine of the type in which cement is supplied to the upper surface of a brush driven on a horizontal axis and the work is presented to a lower surface thereof.

It has been notorious that machines of this general type would accumulate a surplus of cement upon the applying brush when no work was being presented to the machine and that after only a few minutes this surplus would drip to the floor. Such an arrangement is not only wasteful but it is untidy and in the case of certain cements involves added danger of fire.

An object of the invention is to prevent dripping from a rotatable cement applying brush which is supplied from above and to improve the control of the quantity of cement taken from the machine by the brush.

In the illustrated machine a control plate having a transverse opening is inserted between the discharge opening of the container and the top of the brush. The plate is constructed to rub against the tips of the bristles as they leave it thereby to control the quantity of cement delivered and is provided with scraper surface and recesses which draw back toward the center of the brush any cement which has spread out to the margin of the periphery or which tends to run down the sides thereof. The arrangement is such that unused cement is forced back into the receptacle and the margins of the periphery of the brush are kept clean.

These and other features of the invention will best be understood from a consideration of the following description taken in connection with the accompanying drawings in which,

Fig. 1 is a side elevation of the head of a machine in which the present invention is embodied;

Fig. 2 is a similar view, but with parts broken away and on a larger scale, of those parts which are immediately adjacent to the brush;

Fig. 3 is a detail vertical section on the line III—III of Fig. 2;

Fig. 4 is a detail front elevation on the scale of Fig. 2;

Fig. 5 is a vertical section on the line V—V of Fig. 2 enlarged;

Fig. 6 is a view looking up at the underside of the control plate; and

Fig. 7 is a section on the broken line VII—VII of Fig. 5.

In the application of cement to the bottoms of shoes preparatory to the application of soles

thereto, use is made of a cylindrical brush 10 which is mounted on a driven shaft 12 carried in a frame 14 which is mounted at the head of a column 16. As shown, the width of the brush is about half its diameter. Cement is delivered to the upper side of this brush from an inverted receptacle in the form of a can 18 threaded in a cup 20 (Fig. 2) from which the cement flows downwardly through a passage 22 in a neck 23 whenever a valve 24 (Fig. 5) is opened by the proper positioning of a hand lever 26 (Fig. 4). This valve is held in the neck by a cap plate 27. The cements used for this kind of work are frequently quite viscous and, therefore, provision is made for admitting air to the upper surface of the cement in the can 18 through a tube 28 (Fig. 2), while, if desired, a source of compressed air (not shown) may be connected to the tube 28 through an inlet 30 having a hand cock 31.

20 The quantity of cement removed by the brush depends upon the wiping contact of a surface 32 (Fig. 5) at the leaving side of a curved control plate 34 which is interposed between a delivery passage 36 below the valve 24 and the periphery 25 of the brush, this plate being attached by screws 38 to the lower end of the cup 20. The distance between this surface 32 and the center of the brush may conveniently be controlled by mounting the cup 20 and hence the plate 34 for adjustment toward and away from the brush.

To this end the frame 14 of the machine is provided with a bracket 40 (Fig. 2) which is bolted thereto and which is provided with a laterally extending arm 42. In the body of the bracket is a stud 44 having a reduced end 46 on which there is clamped a supporting arm 48 (Fig. 3) which is provided with a forwardly extending ledge 50. The cup 20 is adjustably supported on this ledge 50 by means of clamping screws 52 which pass through slots in an arm 54 extending laterally from the cup and having a down-turned end 56 in which is mounted an adjusting screw 58 which contacts with the end of the ledge 50 and enables careful adjustment in a horizontal direction of the cup and its arm 54 before the clamping screws 52 are tightened. This adjustment will be used primarily in setting up the machine to position the plate 34 so that it is approximately concentric to the brush.

Provision is also made for adjusting the wiping surface 32 of the control plate 34 approximately radially of the brush to control the exact quantity of cement on the brush and to compensate for the wear of the bristles.

For such accurate control, the arm 48 and the

stud 44, 46 to which the arm is clamped may be turned around the axis of the stud 44 when a thumb screw 60 bearing on the stud is loosened. This swinging movement of the arm 48 and the receptacle carried thereby is facilitated by the provision of a finger operated shaft 62 which is journaled in the depending arm 42 of the bracket 40 and which has at its end an eccentric pin 64 received in a notch 66 in the arm 48 and capable of easily producing a small movement of that arm when the thumb screw 60 has been loosened and the finger shaft 62 turned. The exact range of movement of the arm 48 may be determined by means of abutment screws 68 and 70 which are threaded through portions of the arm 48 above and below the notch 66, with their ends in contact with the eccentric pin 64. After these screws have been adjusted to the desired position they are held there by locknuts.

It is intended that the adjustment of the control surface 32 with respect to the bristles shall allow only so much cement to be taken out by the brush as will be used up by work presented to the brush. However, it will be understood that the supply of work is not always constant and that carelessness on the part of an operator may allow the machine to run idle for some few minutes without the valve 24 having been closed in the meantime. Accordingly, the control plate 34 has been constructed to overcome such difficulties. For ease of discussion, the forward portion of this plate is shown in Fig. 7 as formed in three layers but it may equally well be an integral structure. In the first place the plate has a transverse slot 72 in the innermost layer or septum through which the cement normally flows down upon the brush and is removed in such quantities as is permitted by the control surface 32. However, the application of work to the brush may sometimes cause the cement to be spread over the periphery thereof in such a way that quantities accumulate near the marginal corners and even run over the sides of the brush. This difficulty is offset, however, by providing the control plate with shelves spaced vertically from said plate and having along adjacent edges slightly undercut shoulders 74 and 76 which converge forwardly toward the control surface 32 and the delivery opening. The distance between these edges at the entering or right side in Fig. 6 is slightly less than the width of the brush to the end that the ends of the bristles 80 of the brush 10 are squeezed inwardly as they move forwardly. As a result, the cement is urged back toward the central portion of the periphery and if, because of an extended interval between the presentation of pieces of work, there is an undesired quantity of cement on the periphery of the brush, it will be forced upwardly through the delivery opening 72. It will be noted, furthermore, that the spacing

5 of the shelves from the plate or its inner septum 84 provides recesses 82 on each side which widen toward the opening and finally merge with it. Any surplus of cement taken from the peripheral margins or side edges of the bristles may flow into said recesses as it is dragged along by contact with cement on the brush toward the delivery opening 72 into which the recesses open. It will be noted that the control surface 32 is inclined 10 with respect to the circumference of the brush and that as a consequence a transverse pocket 86 is formed in which the cement passing through the delivery opening 72 is taken up by the bristles just before they reach the control surface 32. As the bristles reach this pocket they will be 15 released from the deflecting effect of the shoulders 74, 76 and allowed to spring back to their natural position, the tendency being to keep the useful band of cement near the central portion of the periphery of the brush and to avoid any tendency to apply so much cement to the lateral margins that it might drip when no work is presented to the brush.

20 In the operation of the machine a lasted shoe will be held in inverted position and the shoe bottom will be presented to the lowermost portion of the rotating brush 10 so as to spread cement over the desired area of the shoe bottom.

25 Having thus described my invention, what I claim as new and desire to secure by Letters Patent of the United States is:

30 In a shoe bottom coating machine, a driven cylindrical brush, means for supplying coating material to an upper portion of said brush and a control plate interposed between said supplying means and the brush, said control plate having a delivery slot extending transversely thereof, and having a control surface dragging on the bristles as they leave the plate, the portion of the plate 35 to the rear of said delivery opening having a thin septum, spaced below which are inwardly projecting shelves having forwardly converging adjacent edges for engagement with the sides of the bristles near their tips, said shelves thus providing 40 recesses, between them and the septum, which widen forwardly and open into the delivery opening to permit surplus cement scraped off by the shoulders to move into the recesses and thus travel back to said opening.

45 50 JOHN WILLIAM PRATT.
